DRAPERY ROD FIXTURE

Joseph V. Graber, Madison, Wis., assignor to Graber Manufacturing Company, Inc., Middleton, Wis., a corporation of Wisconsin

Filed Oct. 23, 1961, Ser. No. 146,720

10 Claims. (Cl. 16—94)

This invention relates to drapery fixtures and particularly to an improved traverse rod and support bracket therefor.

An important object of this invention is to provide an improved drapery rod and support bracket therefor which can be mounted flush to the ceiling or other overhead support.

Another object of this invention is to provide an improved drapery rod and mounting bracket in which the mounting bracket is completely concealed from the front of the rod to enhance the appearance of the installed drapery fixture.

Another object of this invention is to provide a drapery rod and mounting bracket therefor which enables easy mounting and removal of the rod from the support.

Still another object of this invention is to provide a drapery rod and mounting bracket therefor and which the mounting bracket can be initially attached to the support surface such as a ceiling or the like, and the rod thereafter mounted on the bracket and adjusted relative to the support in a direction longitudinally of the rod to facilitate location of the rod in the desired position.

The present invention relates to a hollow traverse rod having a longitudinally extending trackway and is characterized by the provision of spaced openings in the rod above the trackway and mounting brackets which extend through the openings and engage the underside of the top wall of the rod to support the same, without interfering with the movement of the slides along the trackway and in such a manner that the mounting bracket is completely concealed from the front of the rod.

These, together with various ancillary objects and features of the present invention will be more readily appreciated as the same becomes better understood by reference to the following detailed description when taken in connection with the accompanying drawings wherein:

FIG. 1 is a fragmentary perspective view of one form of rod and mounting bracket with parts broken away and shown in section to illustrate details of construction;

FIG. 2 is a fragmentary transverse sectional view taken on the plane 2—2 of FIG. 1;

FIG. 3 is a fragmentary perspective view illustrating an auxiliary mounting bracket for use in supporting the rod of FIG. 1;

FIG. 4 is a transverse sectional view taken on the plane 4—4 of FIG. 3;

FIG. 5 is a fragmentary perspective view illustrating a drapery fixture having a modified form of mounting bracket; and

FIG. 6 is a fragmentary rear perspective view of a further modified form of drapery rod and mounting bracket therefor.

The drapery fixture of the present invention in general includes a hollow rod 10 having an elongated slot 11 defining a trackway, and a mounting bracket 12 for supporting the rod. In accordance with the present invention, the rod 10 is formed with openings 13 at spaced points therealong above the trackway 11 and the mounting bracket 12 is formed with rod engaging portions or fingers 14 which extend through the openings 13 and engage the underside of the top wall of the rod to support the same. With this arrangement, the rod can be mounted flush to a ceiling or other overhead and, moreover, the mounting brackets are completely concealed from the front of the

2

rod to thereby enhance the overall appearance of the drapery fixture.

The rod 10 is preferably formed with a generally flat top wall 16 for engaging the ceiling or other overhead and a front wall 17 shaped to simulate a molding or the like. As shown, the front wall 17 is formed with a longitudinally extending bead 18 along the upper side thereof and the front wall merges with a curved bottom wall 19. The slot 11 is preferably formed in the rear wall 21 at a level spaced an appreciable distance below the top wall 16 to provide clearance for the drapery slides 20 mounted in the trackway. For reasons which become apparent as the following description proceeds, the rear wall 21 is advantageously formed with a rearwardly projecting bead 25 along the juncture of the rear wall with the top wall, and which bead has a downwardly and forwardly inclined wall portion designated 22. The openings 13 are formed in this downwardly and forwardly inclined wall portion 22 and, as is clearly shown in FIGS. 2 and 4, the openings 13 are spaced below the top wall 16 of the rod. This provides a ledge or lip 24 which extends downwardly from the top wall of the rod above each of the openings 13, and which is employed in a manner described hereinbelow to prevent lateral withdrawal of the rod from the mounting bracket.

It is contemplated that the opening 13 be formed at uniformly spaced intervals along the rod, for example every six inches, to enable placement of the brackets at any desired location along the rod. The rod support brackets 12 are so arranged that they can be mounted on the support surface such as the ceiling indicated generally by the numeral 31 prior to installation of the rod; the rod thereafter assembled onto the brackets, and the brackets then tightened to clamp the rod in position. In order to avoid the necessity of accurate placement of the brackets and to enable adjustment of the position of the rod after installation, provision is made for adjustably supporting the rod brackets for movement in a direction longitudinally of the rod a distance at least equal to the spacing between adjacent ones of the openings 13 in the rod.

As shown in the embodiment of FIGS. 1 and 2, the rod mounting bracket 12 includes an elongated mounting plate 32 having a pair of the aforementioned rod engaging fingers 14 extending laterally from adjacent opposite ends thereof. The mounting plate 32 is slidably attached to a channel-shaped member 33, which channel-shaped member has openings 34 (FIG. 2) adjacent opposite ends for receiving screws 35 or the like to attach the same to a ceiling or other overhead. The channel-shaped member 33 may be formed of any suitable material such as metal, plastic or the like and has outwardly and inwardly extending flanges 36 and 37 respectively on each of its legs. As best shown in FIG. 2, the mounting plate 32 of the bracket has generally L-shaped flanges 38 and 39 along opposite side edges which slidably engage the outwardly extending flanges 36 on the channel member. A generally T-shaped block or nut 41 is slidably supported on the inwardly directed flanges 37 of the channel member and a fastener such as a screw 42 extends through the mounting plate 32 and into the nut to selectively clamp the bracket to the channel member in any desired adjusted position. As will be noted from FIG. 2, the channel member and nut 41 are dimensioned so that the nut will engage the screws 34 when the nut reaches either end of the channel member, to prevent accidental detachment of the bracket from the channel member. The overall length of the channel member is advantageously made such as to enable adjustment in a direction longitudinally of the rod through a distance at least equal to the spacing between adjacent openings 13 in the rod.

The laterally extending rod engaging fingers 14 are

shaped to facilitate assembly and removal of the rods from the fingers after the mounting brackets have been installed on the ceiling and to also selectively lock the rod against lateral withdrawal from the fingers. As best shown in FIG. 2, the rod engaging fingers 14 are bent intermediate their ends to form a generally U-shaped portion 48 which extends downwardly along the rear side of the rod and then inwardly through the opening 13 and upwardly and terminates in a rod engaging portion 49 which engages the underside of the top wall 16. This forms an upwardly opening depression or seat on each of the fingers which receive the downwardly extending ledge 24 on the rod. The rod engaging portion 49 of the fingers are preferably longitudinally arched to facilitate sliding of the rods onto and off the fingers. It is contemplated that one or more of the brackets 12 be initially mounted on the ceiling or other overhead, at spaced points along the window, and the rod thereafter assembled onto the mounting brackets. Since the mounting brackets 12 are adjustable relative to the supporting surface in a direction longitudinally of the rod, the position of the rod can be shifted as required after it has been assembled on the brackets.

While the rod 10 can be mounted entirely by the use of several adjustable mounting brackets 12, it is more economical to initially mount the rod by one adjustable bracket to facilitate adjustment of the rod to the desired position, and to thereafter attach additional non-adjustable support brackets to the rod as required to adequately support the rod. Such additional support brackets are illustrated in FIGS. 3 and 4 and are designated generally by the numeral 51. The auxiliary brackets each include a mounting plate 52 having an opening 53 therein for receiving a mounting screw 54. A rod supporting finger 57 is formed integrally with the plate 52 and includes a U-shaped portion 56 adapted to extend through one of the openings 13 in the rod and an arched rod engaging portion 57 at the end remote from the plate 52. As shown in FIG. 4, the rod engaging portions of the mounting brackets shift downwardly away from the ceiling when the fastener such as 54 is loosened, and the rod can then be easily assembled on the brackets by merely tilting the rod slightly, as shown in solid lines, while pressing the rod inwardly onto the fingers to the dotted line position.

A modified form of mounting bracket is illustrated in the embodiment of FIG. 5. The rod 10 is the same as that previously described and like numerals are used to designate corresponding parts. The adjustable bracket 12' includes an elongated mounting plate 32' having a pair of rod supporting fingers 14' extending laterally from adjacent opposite ends. As previously described, the rod engaging fingers are bent intermediate their ends to provide a generally U-shaped portion 48' for receiving the ledge 24 on the rod and an arched rod engaging portion 49' for engaging the underside of the top wall of the rod. In this embodiment, the mounting plate is attached directly to the ceiling or overhead and is formed with an elongated slot 33' which receives a mounting fastener such as 35'. While a plurality of such adjustable support brackets could be used to support the rod, it is convenient and more economical to use one adjustable bracket to facilitate initial positioning of the rod and to use additional non-adjustable brackets such as those illustrated and described in connection with FIGS. 3 and 4. These non-adjustable brackets can be used to provide additional support for the rod and can be inserted through the proper openings 13 in the rod and secured to the overhead, after the rod has been initially installed and adjusted by means of the aforescribed adjustable slide.

A further modified form of rod and mounting bracket is illustrated in FIG. 6. In this embodiment, the rod designated generally by the numeral 60 is formed with a generally flat top wall 61, a front wall 62 and a rear wall 63 with a slot 64 in the rear wall spaced below the top wall 61 and defining a trackway. The front wall may

conveniently be shaped in the manner previously described to simulate a molding or the like. In this embodiment, the openings designated 67 are formed in the rear wall 63 closely adjacent the underside of the top wall 61. The mounting bracket 68 is formed with a mounting plate 69 and a pair of laterally extending rod engaging fingers 71 which extend through the opening 67. In order to prevent lateral withdrawal of the rod from the fingers 71, the top wall 61 has an inwardly extending bead or depression 74 on the underside and positioned forwardly of the rear wall 63. The bead or depression is located at least in the region of the openings 67 and may conveniently extend the full length of the rod as shown in the drawings. The fingers 71 extend below the bead or depression 74 and have hook portions 75 at their inner ends arranged to engage the bead to lock the rod against lateral withdrawal from the fingers.

The mounting plate 69 of the bracket 68 is adapted for attachment directly to an overhead ceiling or the like, in the manner previously described in connection with the embodiment of FIGS. 3 and 4 and, as shown, has a longitudinally extending slot 76. The rod and mounting bracket, however, can also advantageously be used on wall installations. As shown, a generally L-shaped wall bracket 81 is adjustably attached to the mounting plate 69 of the bracket 68 by a fastener 82. The wall bracket has a portion 83 which overlies the top wall 61 of the rod, to thereby clamp the top wall of the rod between the fingers 71 and the portion 83. With this arrangement, the rod can be mounted on a wall, window frame or the like at a level spaced below the ceiling and, when installed in this manner, the wall bracket and mounting clamps are effectively concealed from the front of the rod to provide an improved overall appearance.

From the foregoing, it will be seen that the mounting brackets support the rod by engagement with the underside of the top wall and can be advantageously used to support the rods flush to an overhead such as a ceiling. Moreover, the brackets support the rod in such a manner as to be concealed from the front of the rod thereby improving the overall appearance of the fixture when the rod is attached to a ceiling as shown in FIGS. 1 and 5 or when it is attached to a wall as illustrated in FIG. 6. In each of the several embodiments, the rod and the rod engaging fingers are shaped so that the fingers effectively clamp the rod against lateral withdrawal. Additionally, the rod brackets are shaped and arranged so as to not interfere with the movement of the slides or traverse cords along the rod.

I claim:

1. A drapery rod fixture for attachment to the underside of an overhead support comprising, an elongated hollow rod having a flattened top wall and front and rear walls and a longitudinally extending slot spaced below said top wall and defining a trackway, slides mounted in said trackway for movement therewith and having portions projecting into the hollow rod, said rod having a plurality of longitudinally spaced openings in said rear wall above said trackway, means for mounting said rod with its top wall directly abutting an overhead support, said mounting means including a drapery rod support bracket having a mounting portion adapted for attachment to an overhead support and a rod engaging portion extending from said mounting portion and through at least one of said openings into said track above the slides, said rod engaging portion engaging the underside of the top wall of the rod at a point intermediate said front and rear walls for supporting the rod with the top wall abutting the overhead support, said mounting means including a fastener means engaging said mounting portion and extending transverse to a plane through the top wall of the rod for drawing the rod engaging portion upwardly to firmly clamp the top of the rod against the overhead support, and interengaging means on the rod and rod engaging portion of the bracket for locking the rod against

movement relative to the bracket in a direction crosswise of the rod when the rod is clamped to the overhead support.

2. A drapery rod fixture for attachment to the underside of an overhead support comprising an elongated hollow rod having a top wall and front and rear walls and a longitudinally extending slot spaced below said top wall and defining a trackway, slides mounted in said trackway for movement therealong and having portions extending into the hollow rod, said rod having a plurality of longitudinally spaced openings in said rear wall above said trackway, a drapery rod support bracket having a mounting portion adapted for attachment to an overhead support and a rod engaging portion extending through at least one of said openings and into the rod above the slides, said rod engaging portion engaging the underside of the top wall of the rod at a point intermediate said front and rear walls for supporting the rod with the top wall abutting the overhead support, means attaching said mounting portion of said support bracket to an overhead support for adjustment in a direction paralleling the rod a distance at least equal to the spacing between adjacent openings in the rod and for locking said mounting portion in its adjusted position, said attaching means including a fastener extending transverse to a plane through the top wall for drawing the rod engaging portion upwardly to press the top of the rod against the overhead support.

3. A drapery rod fixture for attachment to the underside of an overhead support comprising an elongated hollow rod having a top wall and front and rear walls and a longitudinally extending slot spaced below said top wall and defining a trackway, slides mounted in said trackway for movement therealong and having portions extending into the hollow rod, said rod having a plurality of longitudinally spaced openings in said rear wall above said trackway, a drapery rod support bracket having a mounting portion adapted for attachment to an overhead support and a rod engaging portion extending through at least one of said openings and into the rod above the slides, said rod engaging portion engaging the underside of the top wall of the rod at a point intermediate said front and rear walls for supporting the rod with the top wall abutting the overhead support, said mounting portion extending generally parallel to said rod and having an elongated slot extending lengthwise thereof, and a fastener extending upwardly through said slot in a direction transverse to a plane through the top wall of the rod for engagement with an overhead support to support the bracket for adjustment in a direction paralleling said rod, said fastener being operative when tightened to lock said bracket against movement and to draw the rod engaging portion upwardly to press the top of the rod against the overhead support.

4. A drapery rod fixture for attachment to the underside of an overhead support comprising an elongated hollow rod having a top wall and front and rear walls and a longitudinally extending slot spaced below said top wall and defining a trackway, slides mounted in said trackway for movement therealong and having portions extending into the hollow rod, said rod having a plurality of longitudinally spaced openings in said rear wall above said trackway, a drapery rod support bracket having a mounting portion adapted for attachment to an overhead support and a rod engaging portion extending through at least one of said openings and into the rod above the slides, said rod engaging portion engaging the underside of the top wall of the rod at a point intermediate said front and rear walls for supporting the rod with the top wall abutting the overhead support, said mounting portion extending generally parallel to said rod and having opposed inwardly directed flanges along opposite sides, a channel-shaped guide member having a first pair of outwardly directed flanges on the legs thereof and a second pair of inwardly directed flanges, said flanges on said mounting portion loosely engaging said first pair of legs

to support the mounting portion for adjustment in a direction longitudinally of the rod, a slide block slidably mounted on said second pair of legs, and a fastener extending through said mounting portion in a direction transverse to a plane through the top wall of the rod and engaging said block for locking the mounting portion to the guide member and for drawing the mounting portion upwardly to press the top of the rod against the overhead support.

5. A drapery rod fixture comprising, an elongated hollow rod having a top wall and front and rear walls and a longitudinally extending slot spaced below said top wall and defining a trackway, slides mounted in said trackway for movement therealong and having portions extending into the hollow rod, said rod having a plurality of longitudinally spaced openings in said rear wall above said trackway, a drapery rod support bracket having an elongated mounting portion and at least two rod engaging portions extending laterally from the mounting portion at spaced points therealong, said rod engaging portion extending through spaced ones of said openings in said rod above the slides and into engagement with the underside of the top of the rod to support the same, means attaching said mounting portion of said support bracket to an overhead support for adjustment in a direction lengthwise of the mounting portion a distance at least equal to the spacing between adjacent openings in the rod and for selectively locking said mounting portion of the bracket in its adjusted position, said attaching means including a fastener extending transverse to a plane through the top of the rod and operative to draw the rod engaging portion upwardly to press the top of the rod against the overhead support.

6. In combination, an elongated hollow rod having a top wall and front and rear walls and a longitudinally extending slot in the rear wall spaced below the top wall and defining a trackway, slides mounted in said trackway for movement therealong and having portions extending into said hollow rod, said rear wall having a plurality of longitudinally spaced openings therein spaced above the trackway and spaced below the top of the rod to form a depending lip on the rod above each opening, a drapery rod support bracket having a mounting portion and a rod engaging finger extending from said mounting portion, said rod engaging finger having a U-shaped portion intermediate its ends extending through one of said openings and straddling said lip above the opening in the rod to clamp the rod against movement relative to the mounting portion, said finger having a rod engaging portion at the end remote from the mounting portion disposed above said slides and engaging the underside of the top wall of the rod to support the rod, and means including a fastener extending upwardly through said mounting portion for attaching said mounting portion to an overhead support and for drawing the rod engaging finger upwardly to clamp the rod to the overhead support.

7. In combination, an elongated hollow rod having a top wall and front and rear walls and a longitudinally extending slot in the rear wall spaced below the top wall and defining a trackway, slides mounted in said trackway for movement therealong and having portions extending into said hollow rod, said rear wall having a bead adjacent its juncture with said top wall and defining a wall portion disposed above the trackway and inclined downwardly and forwardly from adjacent the rear edge of the top wall, said rear wall having a plurality of longitudinally spaced openings in said wall portion above the trackway and spaced below said top wall to form a depending lip above each opening, and a drapery rod support bracket having a mounting portion and a rod engaging finger extending from said mounting portion, said rod engaging finger having a U-shaped portion intermediate its ends extending through one of the openings and straddling said lip above the opening in the rod to clamp the rod against movement relative to the

mounting portion, said finger having a rod engaging portion at the end remote from the mounting portion disposed above said slides and engaging the underside of the top wall of the rod to support the rod, and means including a fastener extending upwardly through said mounting portion for attaching said mounting portion to an overhead support and for drawing the rod engaging finger upwardly to clamp the rod to the overhead support.

8. In combination, an elongated hollow rod having a top wall and front and rear walls, said rod having an elongated slot therein spaced below said top wall and defining a trackway, slides mounted in said trackway for movement therealong and having portions extending into said hollow rod, said rear wall having a plurality of longitudinally spaced openings therein spaced above the trackway, said rod having means defining a rib extending downwardly below the level of the top wall at least in the region adjacent the openings in the rod, a drapery rod support bracket having a mounting portion and a first rod engaging finger extending from said mounting portion, said first finger having a saddle portion extending into one of said openings in said rod and straddling said rib and engaging the underside of the rod to support the same, and a fastener extending through said mounting portion in a direction transverse to a plane through the top wall of the rod for drawing the said first finger upwardly to clamp the same to an overhead support.

9. The combination of claim 8 wherein said rib is located at the underside of the top wall intermediate the front and rear edges of the top wall.

10. In combination, an elongated hollow rod having a top wall and front and rear walls, said rod having an elongated slot therein spaced below said top wall and defining a trackway, slides mounted in said trackway for movement therealong and having portions extending into said hollow rod, said rear wall having a plurality of longitudinally spaced openings therein spaced above the trackway, said rod having means defining a rib extending downwardly below the level of the top wall at least in the region adjacent the openings in the rod, a drapery rod support bracket having a mounting portion and a first rod engaging finger extending from said mounting portion, said first finger having a saddle portion extending into one of said openings in said rod and straddling said rib and engaging the underside of the rod to support the same, said mounting bracket including a second rod engaging finger overlying the top wall of the rod and terminating rearwardly of the front wall of the rod, and a fastener extending through said mounting portion in a direction transverse to a plane through the top wall of the rod and into said second rod engaging finger for drawing said first rod engaging finger upwardly to clamp the same to said second finger.
